UNITED STATES PATENT OFFICE.

LOUIS DESMARAIS, OF NEW YORK, N. Y.

SPIRIT-LEVEL.

SPECIFICATION forming part of Letters Patent No. 650,751, dated May 29, 1900.

Application filed November 15, 1899. Serial No. 737,110. (No model.)

To all whom it may concern:

Be it known that I, LOUIS DESMARAIS, a subject of the Queen of Great Britain, and a resident of the city of New York, borough of 5 Manhattan, in the county and State of New York, have invented a new and Improved Spirit-Level, of which the following is a full, clear, and exact description.

This invention relates to improvements in 10 spirit-levels and plumb-rules; and the object is to provide a device of this character that shall be of simple construction and so arranged that it may be easily taken apart for repairs or other purposes and as easily assembled or put together.

I will describe a spirit-level embodying my invention and then point out the novel features in the appended claim.

Reference is to be had to the accompanying 20 drawings, forming a part of this specification, in which similar characters of reference indicate corresponding parts in all the figures.

Figure 1 is a side elevation of a level embodying my invention. Fig. 2 is a section on 25 the line 2 2 of Fig. 1. Fig. 3 is a section on the line 3 3 of Fig. 2. Fig. 4 is a section on the line 4 4 of Fig. 3, and Fig. 5 shows the device as arranged for a plumb-rule.

The device comprises a body portion 1, 30 of wood or other suitable material, having straight parallel sides, as is usual in these instruments. Seated in an opening 2, formed through the body portion, is a metal tube 3 for holding the glass 4 for the bulb. The 35 bulb-glass is here shown as having its ends extended into plaster or other sealing material 5, placed in opposite outward openings in the side walls of the tube. By this construction a new tube may be easily inserted in an 40 old tube or ring 3 by removing the plaster, putting in the bulb-tube, and then placing in new plaster. Of course in inserting the new bulb-tube in a new ring 3 the same operation takes place, except that there is no old plaster to remove.

The openings in the side walls of the tube 3 completely surround the side sight-opening and are unobstructed, as shown best in Fig. 3, so that the bulb-tube may be placed 50 at the bottom or on any side of the said sight-

opening, or two tubes of suitable size may be inserted, one extending at right angles to the other.

The tube or holder 3 has an inner flange 6, adapted to engage with an inner shoulder 7, 55 formed in the wall of the opening through the body portion. As a means for removably holding the part 3 in place I have here shown screw-bolts 8, which at one end have washers 9 for engaging with the flange 6, and at the 60 opposite end the screw-bolts are engaged by nuts 10. After the device is secured in place, as above described, ring-plates 11 12 may be attached to the body portion at opposite sides, as clearly shown in the drawings. The bulb- 65 tube may be placed lengthwise of the body portion when the device is to be used as a spirit-level, or it may be placed transversely of the body portion when the device is to be used as a plumb-rule, as shown in Fig. 5, and 70 obviously two or more of the tubes 4 may be placed in a single body portion, so that one tool will serve both as a leveling and a plumb-ing instrument.

For convenience a sight-hole may be formed 75 through the top of the body portion of the level and through the upper wall of the tube 3, as shown in the drawings, so that the bulb may be seen from the top when it is not practical to see it from either side.

Having thus described my invention, I claim as new and desire to secure by Letters Patent—

A leveling or plumbing instrument, consisting of a body portion having an opening 85 therethrough, a tube arranged to fit in said opening and formed with a central sight-opening and uninterrupted openings in its side walls which completely surround said sight-opening, a bulb-tube inserted in the openings 90 in the side walls, and cement filling up said side-wall openings, as and for the purpose set forth.

In testimony whereof I have signed my name to this specification in the presence of 95 two subscribing witnesses.

LOUIS DESMARAIS.
